UNITED STATES PATENT OFFICE.

CHARLES E. WISE, OF PARKERSBURG, WEST VIRGINIA, ASSIGNOR OF ONE-HALF TO JAMES K. FLETCHER, OF PARKERSBURG, WEST VIRGINIA.

CAR-REPLACER.

SPECIFICATION forming part of Letters Patent No. 784,647, dated March 14, 1905.

Application filed October 12, 1904. Serial No. 228,183.

To all whom it may concern:

Be it known that I, CHARLES E. WISE, a citizen of the United States, residing at Parkersburg, in the county of Wood and State of West Virginia, have invented a new and useful Car-Replacer, of which the following is a specification.

This invention relates to devices employed for replacing derailed cars upon the rails, and 10 has for its object to improve the construction and increase the efficiency of devices of this character.

With these and other objects in view, which will appear as the nature of the invention is better understood, the same consists in certain 15 novel features of construction, as hereinafter fully described and claimed.

In the accompanying drawings, forming a part of this specification, and in which corresponding parts are denoted by like designating characters, is illustrated the preferred 20 form of the embodiment of the invention capable of carrying the same into practical operation, it being understood that the invention 25 is not necessarily limited thereto, as various changes in shape, proportions, and general assemblage of the several parts may be resorted to without departing from the principle of the invention or sacrificing any of its 30 advantages.

In the accompanying drawings, Figure 1 is a plan view of the member to extend between the rails. Fig. 2 is a transverse sectional view of the same. Fig. 3 is a plan view of the member to be placed outside the rail. Fig. 4 is a 35 transverse sectional view of Fig. 3. Figs. 5 and 6 are perspective views, on a reduced scale, of the two members comprising the improved device.

40 The improved device comprises two members represented, respectively, at 10 and 11, said members being preferably formed of cast-steel and each member provided with a platform sloping in opposite directions from a central point 12 downwardly toward the ends 45 13 and 14. Each member is provided with a web 15 along one side thereof, having a longitudinal channel 16 for engagement with the heads of the rails 17, the platforms of said

members being inclined in a downwardly-curving line 18 from the point 12 to the rail-engaging web 15. Each member is also inclined to a horizontal plane at the side opposite the web 15, as indicated at 19, and provided with a wheel-flange engaging stop-rib 55 20, disposed along the line of juncture of the reversely-inclined surfaces, there being a hand-hole 21 in each sloping side to assist in handling the members. The downwardly-curving surface 18 of one member 11 merges at the 60 center into the upper surface of the web 15 to carry the wheel-flange over the head of the rail, as indicated at 22, while the member 14 is provided with a longitudinal channel 23 between the web 15 and the downwardly-curving surface 18 of the same to receive the wheel-flange and prevent the wheel of the car from riding the rail.

In using the device the member 10 is placed between the rails 17 and seated on the ties 24 70 adjacent to the wheels of the derailed car or other vehicle, while the member 11 is placed on the ties outside the opposite rail. As the derailed car is drawn forward the wheels run upon the inclined surfaces and their flanges 75 are guided by the ribs 20 upon the downwardly-curving surface 18 and caused to slide laterally thereover by gravity, and as the car continues to move forward the wheels are guided into position upon the rails. The members 10 and 11 are relatively wide at the ends 80 13 and 14, so that they will receive the derailed wheels of the car when positioned at a considerable distance from the rails, thus naturally increasing the scope of the device. 85 The members are also preferably long enough to extend over at least two of the ties 24, so as to afford ample support for the same. It will be observed that the portion 12 of the member 11 is higher than the corresponding portion of the member 10, so that the derailed car will be caused to move laterally with greater force, and thus insure proper movement of the latter while mounting the members.

90 The outer side of the web 15, forming the outer wall of the channel 16, is relatively long or depending and extends nearly to the tie-

flanges of the rails, so as to increase the stability of the replacer and lessen the tendency to overturn under the severe strains to which devices of this class are subjected. Spurs 25 are also provided on the lower edges of the device to engage the ties 24 and assist in preventing accidental displacement of the replacer.

Having thus described the invention, what is claimed is—

A car-replacer comprising a pair of members each provided with a platform inclined from the center downwardly toward its opposite ends and having a web along one side thereof provided with a longitudinal channel for engagement with the head of the rail, the opposite side of the platform being inclined

to a horizontal plane and provided with a guiding-rib along the juncture of said inclined side and the adjacent surface of the platform, said platforms being likewise inclined in a downwardly-curving line between the centers of the guiding-ribs and said engaging webs, one of said members having a channel between its longitudinal web and the inclined surface of the adjacent platform for the reception of the flange of the car-wheel.

In testimony that I claim the foregoing as my own I have hereto affixed my signature in the presence of two witnesses.

CHARLES E. WISE.
